(57) **CLAIM**

The ornamental design for a body composition meter, as shown and described.

DESCRIPTION

FIG. 1 is a front, right side, top perspective view of a body composition meter showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a perspective view thereof showing a state in which electrodes for hands are detached from a body portion of this article.
